UNITED STATES PATENT OFFICE.

VIRGIL COBLENTZ AND HAROLD W. WALKER, OF NEW YORK, N. Y., ASSIGNORS TO COMMERCIAL RESEARCH COMPANY, OF NEW YORK, N. Y., A CORPORATION OF NEW YORK.

SIDE-CHAIN OXIDATION.

1,332,028

Specification of Letters Patent. Patented Feb. 24, 1920.

No Drawing.

Application filed April 7, 1919. Serial No. 288,214.

To all whom it may concern:
Be it known that we, VIRGIL COBLENTZ and HAROLD W. WALKER, citizens of the United States, VIRGIL COBLENTZ being a resident of 5 New York, in the county of New York and State of New York, and HAROLD W. WALKER being a resident of New York, in the county and State of New York, have invented certain new and useful Improvements in Side-10 Chain Oxidation, of which the following is a specification.

This invention relates to side-chain oxidation; and it comprises a method of oxidizing side-chains or aliphatic groups carried by 15 aromatic or cyclic hydrocarbon groups, such as the CH_3 group of toluene ($\text{C}_6\text{H}_5\text{CH}_3$), to form acids, wherein the material to be oxidized is stratified with nitric acid of moderate strength, best, around 40 per cent. 20 HNO_3 , and allowed to remain in quiet contact therewith, for a relatively long period at a rather high temperature, the operation being carried out under a reflux condenser or other conditions allowing return of vapors for further action and in the presence 25 of air or oxygen to oxidize evolved lower oxids of nitrogen; all as more fully herein-after set forth and as claimed.

Toluene, $\text{C}_6\text{H}_5\text{CH}_3$, can be converted into 30 benzoic acid, $\text{C}_6\text{H}_5\text{CO}_2\text{H}$, by oxidation with weak nitric acid, but the yields are very poor, only a few per cent. of theory being obtained by the described methods. Strong nitric acid converts toluene into nitro compounds to a greater or less extent. The usual 35 commercial way of making benzoic acid from toluene is first to convert the toluene into a chlorinated derivative and then oxidize this body. The official requirements, 40 however, for benzoic acid laid down in the various pharmacopoeias require a chlorin-free material and it is difficult to produce this by the oxidation of chlorinated derivatives of toluene.

45 We have found that, contrary to the usual view, benzoic acid can be produced in large yield, practically a theoretical yield, by direct oxidation of toluene with nitric acid under regulated conditions without the necessity of preliminarily chlorinating the toluene. In so doing, a chlorin-free benzoic acid is readily produced.

In a practical embodiment of our method, we simply stratify toluene and nitric acid 50 of moderate strength together and leave

them undisturbed at rather a high temperature for some time. Working at a temperature of about 90° C. with a nitric acid of 38 per cent. HNO_3 , under a reflux condenser, complete oxidation usually takes four or 60 five days. The reaction is somewhat longer in starting with fresh nitric acid, and with fresh nitric acid it is advantageous to add a catalyst or body serving to start the evolution of nitrous vapors. Ordinary formaldehyde solution, or paraformaldehyde, may 65 be employed. However, any other material (copper, zinc, starch, etc.) serving to initiate a reduction of the nitric acid will do. But we find the use of solid paraformaldehyde 70 to be the best, since it gives a quick initial reduction of the nitric acid starting the reaction and it does not contaminate the solution. With return of acid, which has already served for one operation, for admixture 75 with fresh acid, the operation is considerably shortened. The greater the surface of contact between the overlying toluene and the underlying nitric acid, other things being equal, the shorter the period 80 required for oxidation. The oxidation is, at least in large part, dependent on the oxidizing action of vapors of nitrogen oxids passing upward into the layer of toluene. Nitrous vapors, that is vapors of the various 85 nitrogen oxids, may be introduced into the toluene from another source; that is, instead of using nitric acid, vapors of these oxids may be used. However, the use of nitric acid itself in the manner described we consider 90 a desirable mode of operation since it gives the vapors, so to speak, *in statu nascendi*. Passing beyond the toluene, the vapors are reoxidized by the air present and, 95 with operation under a reflux condenser, the reoxidized vapors are returned to the reaction zone for service anew. In ordinary operation, considerably more than the calculated oxidizing value can be obtained 100 from a given amount of nitric acid because of this aerial oxidation of these vapors. Stirring the reaction mixture is inadvisable as interfering with the regularity of operation. For one thing, it disturbs the stratification, stirring the two layers into each 105 other; and for another, it causes a temporary rapid disengagement of oxidizing gases or vapors without opportunity for effective contact with the toluene. Instead of returning the condensed vapors by a reflux to the 110

body of liquids from which they originated, they of course may be sent into another similar body, as by the use of the ordinary Woulfe bottle arrangement. The different bodies of material may be out of phase with each other; that is, they may be of different ages. For example, vapors coming from materials which have been under treatment for a day may be led into a fresh batch.

10 The layer of toluene lying above the acid is gradually converted into benzoic acid and finally becomes a solid crust of crystallized crude benzoic acid, usually containing more or less toluene and some benzaldehyde. As 15 the action goes on, the specific gravity of the oily layer becomes greater because of the solution of benzoic acid therein but as long as the materials are kept hot, it does not tend to settle. The progress of the reaction 20 can be ascertained by dipping a cold glass rod into the oily layer. At the end of the action the oily layer tends to become solid even while hot. Any suitable arrangement may be employed for maintaining the temperature of the materials.

A strength of around 40 per cent. of nitric acid is considered best for the present purposes. For good operation the practical limits may be considered between 36 per 30 cent. and 43 per cent. As the oxidation goes on, the strength of the acid lessens until at the end it may be as low as 12 per cent., although it is more usually 16 to 18 per cent. It somewhat accelerates the action to 35 strengthen the underlying acid layer after 1 or 2 days running. A good charge for 100 pounds of toluene is about 1 carboy (140 pounds, approximately) of nitric acid of 42° Baumé and 110 pounds of spent acid containing about 12 per cent. nitric acid.

40 With the use of spent acid containing lower oxids of nitrogen, organic matter, etc., no starting catalyst is necessary, although it may of course be added. Using fresh acid, 100 45 pounds of toluene and about 250 pounds of 38 per cent. nitric acid may be employed. About 0.10 per cent. paraformaldehyde may be added, the additions being in small portions from time to time. With acid stronger 50 than about 43 per cent., there is too much side reaction in the way of nitration, that is, production of nitrocompounds and the like, while with acids much weaker than 35 per cent., the action is entirely too slow. With 55 acid as weak as 20 per cent., it is almost impossible to start the action.

As toluene boils at 110° C., it is usually inconvenient, unless unusually efficient refluxing means or pressure be employed, to 60 operate much above, say, 105° C. A temperature of 95° to 98° C. in working under the usual pressure with the usual condensing means is convenient. In working under pressure, somewhat higher temperatures may 65 be employed with consequent quickening of

the operation. The extra pressure when employed should be air pressure, air being forced into the apparatus by a suitable pump. This gives a greater body of oxygen for regenerating the nitrous fumes. A great 70 economy in acid may be effected by introducing into the apparatus a body of oxygen itself under pressure. However, a very substantial degree of oxidation with much economy of acid is effected by working at the 75 ordinary pressure in an apparatus having an air space several times the volume occupied by the liquids. Temporary fluctuations in pressure due to fluctuations in temperature will provide fresh air in the apparatus 80 as fast as the oxygen is used up by the acid.

After the completion of the oxidation the materials are cooled and the spent acid removed from the solid crystalline crust of benzoic acid and admixed oil (a mixture of 85 unchanged toluene, benzaldehyde, etc.), and returned for use in diluting strong nitric acid. As stated, the strength of this nitric acid is from 12 to 18 per cent. of real acid and a small addition of ordinary commercial 90 acid suffices to bring it up to the preferred 38 per cent. A mixture of spent acid which contains some dissolved organic bodies with fresh acid starts reaction much more quickly than fresh acid diluted with water. The 95 crystalline crust is next treated to convert the benzoic acid into benzoate of soda. For this purpose, it is taken up by a solution of sodium carbonate (soda ash) or caustic soda, as convenience may dictate. An oily layer 100 of toluene, benzaldehyde, etc., which separates from the aqueous layer is returned for admixture with fresh toluene.

It will be noted that in the present method there is no substantial waste, either of acid 105 or of toluene. The conversion of the toluene into benzoic acid is, practically speaking, quantitative, while the acid, as stated, functions to an extent somewhat more than its calculated oxidizing power by reason of 110 the regeneration mentioned. Such losses of either material as occur are mostly mechanical. Operating in the manner described, losses due to nitration are very small. Such 115 nitration as occurs under the prescribed conditions is mostly in the side-chain.

The solution of sodium benzoate may contain nitrocompounds which may be removed by treatment with a reducing agent, such as sodium acid sulfite, crude calcium sulfid 120 (liver of sulfur), tin and hydrochloric acid, etc. By this reduction the nitrocompounds are converted into amino compounds which are readily removed. It may then be acidulated and benzoic acid recovered in the usual 125 way. Sulfuric acid, niter cake (sodium hydrogen sulfate), etc., may be employed for acidulation. Hydrochloric acid may be employed but in its presence greater care is necessary in order to obtain a chlorin-free 130

final product. However, the sodium chlorid is readily removed by washing, differing in this respect from the chlorination products occurring when a chlorinated toluene is oxidized. The spent nitric acid from the operation itself may be employed as an acidulating means in decomposing sodium benzoate. It serves well for this purpose, although at times it contains organic bodies which may yellow the product a little. In using this nitric acid, therefore, as in the case of using hydrochloric acid, good washing must be resorted to. The benzoic acid recovered may be purified by sublimation, crystallization, etc., in the usual ways. The benzoic acid produced of course contains no chlorinated compounds.

Instead of forming benzoic acid from the solution of sodium benzoate in the manner described, sodium benzoate itself may be recovered from the solution in any appropriate way and marketed as such.

Instead of forming sodium benzoate from the crude benzoic acid produced in the described process, calcium benzoate may be produced by the use of milk of lime, chalk, etc. Or, the material may be simply treated with enough soda, lime, chalk, etc., to neutralize the nitric acid present and the benzoic acid recovered and purified in any suitable way.

While the present invention has been described more particularly in its application to the manufacture of benzoic acid from toluene, it may of course be applied to other side-chain derivatives of benzene (benzol), such as ethylbenzene; and it may be applied to the manufacture of other acids than benzoic acid. For example, orthonitrotoluene on oxidation with nitric acid in an analogous manner gives orthonitrobenzoic acid from which, by reduction, anthranilic acid (or orthoaminobenzoic acid) may be obtained; the latter being a valuable material in the indigo synthesis. In addition, the same type of reaction may be utilized for the preparation of valuable local anesthetics of the amino benzoic series. With this material as with others boiling at higher temperatures than toluene somewhat higher temperatures may be employed in the oxidation, with consequent acceleration of the process. With materials of greater specific gravity than that of the nitric acid used in order to obtain the desired stratification an expedient may be used, this expedient consisting in dissolving sodium nitrate in the acid. By oxidizing one of the xylols in a

similar manner to that above indicated toluic acid may be obtained and this, upon further oxidation, is converted into the corresponding phthalic acid. The process is not applicable to the phenols, such as cresol, unless the phenol group be protected by esterification; in which event from ortho-cresol salicylic acid is obtained.

What we claim is:—

1. The process of oxidizing organic aromatic bodies having side-chains with nitric acid to produce acids, which comprises stratifying such organic bodies with nitric acid of a strength between 20 and 43 per cent. HNO_3 and maintaining the two in contact at a high temperature until reaction is complete. 75

2. The process of oxidizing organic aromatic bodies having side-chains with nitric acid to produce acids, which comprises stratifying such organic bodies with nitric acid of about 40 per cent. strength and maintaining the two in contact at a high temperature until reaction is complete. 80

3. The process of making benzoic acid from toluene which comprises stratifying toluene with between 20 and 43 per cent. HNO_3 nitric acid at a temperature somewhat below the boiling point of toluene and allowing the acid and toluene to remain in contact until the reaction is substantially complete. 85

4. The process of making benzoic acid from toluene which comprises stratifying toluene with between 20 and 43 per cent. HNO_3 nitric acid at a temperature somewhat below the boiling point of toluene and allowing the acid and toluene to remain in contact until the reaction is substantially complete, 90 escaping vapors being condensed and returned to the materials undergoing reaction.

5. The process of making benzoic acid from toluene which comprises stratifying toluene with hot nitric acid of about 40 per cent. strength containing a little reducing agent and allowing the two to remain in contact hot until the reaction is substantially complete. 100 105

6. The process of making benzoic acid from toluene which comprises stratifying toluene with hot nitric acid of about 40 per cent. strength containing a little formaldehyde and allowing the two to remain in contact hot until the reaction is substantially complete. 110

In testimony whereof we affix our signatures hereto.

VIRGIL COBLENTZ.
HAROLD W. WALKER.
